[57] CLAIM

The ornamental design for a knife handle, as shown and described.

DESCRIPTION

FIG. 1 is a front perspective view of knife handle showing my new design;
FIG. 2 is a rear perspective view thereof;
FIG. 3 is a front elevational view thereof;
FIG. 4 is a top plan view thereof;
FIG. 5 is a bottom view thereof;
FIG. 6 is a cross-sectional view taken along the line 6—6 in FIG. 3;
FIG. 7 is a left side elevational view thereof;
FIG. 8 is a right side elevational view thereof;
FIG. 9 is a cross-sectional view taken along the line 9—9 in FIG. 3; and,
FIG. 10 is a front elevational view thereof, wherein the broken line showing of the blade is for illustrative purposes only and forms no part of the claimed design.
